UNITED STATES PATENT OFFICE.

AUGUST WUTHE, OF BERLIN, GERMANY.

RAILWAY-COUPING.

SPECIFICATION forming part of Letters Patent No. 697,124, dated April 8, 1902.

Application filed May 11, 1901. Serial No. 60,093. (No model.)

To all whom it may concern:

Be it known that I, AUGUST WUTHE, a subject of the King of Prussia, Emperor of Germany, residing at Berlin, in the Kingdom of Prussia, Germany, have invented certain new and useful Improvements in Railway-Couplings, of which the following is a specification.

My present invention relates to a coupling for railway carriages and trucks; and it consists of the new construction and arrangement of parts hereinafter described with reference to the accompanying drawings, in which—

Figure 1 is a plan view of the coupling parts secured on the ends of two trucks. Fig. 2 is a longitudinal section of Fig. 1; Fig. 3, a longitudinal section of the coupling, showing the various parts in the coupled position; Fig. 4, an end view and side elevation of the coupling parts; and Figs. 5 and 6 represent sections of a modified form of coupling in the uncoupled and coupled position, respectively.

The coupling parts comprise two U-shaped hooks, one secured to the end of each truck by being attached to a cross-beam carried by the buffers of the trucks, and a plate consisting of a number of cross-bars jointed together, which on the two trucks colliding with each other is automatically or manually lowered so as to enter into the U-shaped hooks of both of the trucks. In order to enable the passing of curves, vertical rollers are mounted in the U-shaped hooks as bearing-surfacing for the articulated plates. By releasing a pawl and ratchet the articulated plates can be raised, and in this manner the two trucks will be uncoupled.

In the accompanying drawings similar numerals refer to similar parts throughout the several views with reference to Figs. 1-4.

The hooks 1 are each secured to a cross-beam 3, sliding on ball-bearings in the hollow cross-beam 2, and the articulated plate 4, which is connected with the chain-wheel 5, secured on the shaft 6, carried by the hooks 1, rests on the chains 7, mounted on the chain-wheels 5. The articulated plate 4 is lowered in the direction of the arrow when the hooks 1 of the other truck bear against the angle-irons 10, jointed to the chains 7. The angle-irons 10 are thus pressed inward, and their free ends bear against a plate 11,

which is kept in its normal position by a spring, as shown in Figs. 2 and 3. By means of this inward motion of the angle-irons 10 the chains 7 are rotated in the direction of the arrow 12. In this manner the articulated plate 4, which is jointed to the chain-wheels 5, is lowered into the position shown in Fig. 3. As the articulated plate 4 of the other truck is lowered in the same manner, the position of the parts will be that shown in Fig. 3, and the two trucks will accordingly be coupled together. In the hooks 1 are vertically mounted the rollers 14, and the articulated plates 4 bear against these rollers when in the lowered position. (Represented in Fig. 3.) In this manner the plates 4 can move laterally somewhat, and thus enable the trucks to pass curves. The chains 7, mounted on the chain-wheels 5, also pass around chain-wheels 15, secured on a spindle 16, carried by the bracket 17 on the cross-beam 2. The brackets 17 are secured to a longitudinally-adjustable plate 18. On the cross-beam 2 is also provided a device for raising the articulated plate 4. This device consists of a shaft 19, mounted in the manner shown in Fig. 4 or in any other suitable manner, and of chain-wheels 20, over which the chains 21 pass which are jointed to the articulated plate 4. On the shaft 19 is also secured a spring 22, which is wound up on the articulated plate 4 being lowered and serves for raising the said plate when it is desired to uncouple the trucks. On the shaft 19 is also provided a ratchet-wheel 23, in which a pawl 25, acted on by a spring 24, normally engages. An angle-piece 26 is secured on the beam 2 and limits the upward movement of the plate 4. Springs 27 are secured on the bearings of the shaft 6 in order to guide the plate 4 into the proper position in the hooks 1 and to prevent the plate 4 from being caught by any part. The articulated plates 4 are of such a thickness that each can fall into the proper position in the hooks without becoming jammed together.

The cross-beam 2 is guided on the buffers 29 by the ribs 28. The hooks 1, secured to the beam 3, which slides in the hollow cross-beam 2, the plate 4, chain-wheels 5 and 15, and plate 18 can be adjusted laterally, so that the coupling organs can be secured on either

the right or the left side of the truck, according to circumstances. The chain-wheels 20 can also be laterally moved on the shaft 19. In order to secure the coupling parts in either 5 the left or right hand position, hooks 30 and corresponding eyes are provided, as shown in Fig. 4. The position of the cross-beam 2 is regulated by the buffers 31 and the chains 32. On two trucks colliding together the beam 2 is pushed in until the parts have been coupled. When the trucks are coupled, the cross-beams 2 are moved somewhat toward each other, and for this reason the articulated plates 4 are each jointed to their corresponding chain-wheels 5 by means of a pin and slot, as shown in Fig. 3, thus admitting of a certain movement of the parts and avoiding fracture.

In the modification shown in Figs. 5 and 6 20 the coupling is not effected automatically, but by hand. The articulated plate 4 is released by hand and falls, by reason of its own weight, into the hooks 1. By reason of this arrangement the construction is much simplified, because the wheel 5 only serves in 25 this case as a guide for the articulated plates 4, and the chain 7 and other parts serving the purpose of automatically lowering the plate are unnecessary.

30 As will be seen by reference to Figs. 5 and 6 of the drawings, the articulated plate 4 is only secured by the chains 21 to the device by which it is raised and loosely rests upon the disks or wheels 5, mounted on the hooks 1. On the bearings of the disks 5 are secured the springs 27, as in the construction shown in Figs. 1 to 4, and these springs serve in the modified construction likewise for guiding the articulated plate 4 into the hooks 1. 35 On the shaft 19 is secured a crank 30, by which the chain-wheel 20 is actuated. In this construction the articulated plate is likewise raised by means of the spring secured on the shaft 19, which is wound up on the articulated plate 4 being lowered. In order to 40 prevent the plate from being raised before it is desired to uncouple the trucks, a ratchet and pawl may be provided, as in the construction shown in Figs. 1 to 4, or any other 45 equivalent device may be employed for the purpose. Because in this construction the ends 9 of the hooks 1 bear against the beam 3, which slides in the hollow beam 2, plates 50 10 are provided on the beam 3 of such dimensions that when the ends 9 of the hooks 1 press against the slide-beam the hooks 1 are in the correct position for coupling the trucks. The crank 30 is then rotated and the plate 4 lowered into the hooks, whereupon the trucks 55 60 will be coupled together, as in the former construction. The other parts of this modified construction correspond with those described with reference to Figs. 1 to 4, so that it is unnecessary to again describe the same with reference to Figs. 5 and 6.

What I claim, and desire to secure by Letters Patent of the United States, is—

1. A coupling for railway-carriages and for trucks comprising in combination a cross-beam 2 mounted on and guided between the 70 buffers, U-shaped hooks 1 suitably mounted on the end of the carriage or truck, an articulated plate 4 resting on the chain-wheels 5 to which it is also jointed, angle-irons 10 jointed to the chain on the chain-wheels 5 and adapted 75 to be moved by the hooks 1 on the carriages or trucks colliding together and thus to turn the chain-wheels 5 and lower the plate 4 into the hooks 1, substantially as and for the purpose set forth. 80

2. A coupling for railway carriages and trucks comprising in combination a cross-beam 2 mounted on and guided between the buffers, a cross-beam 3 sliding in the cross-beam 2, U-shaped hooks 1 secured to the 85 cross-beam 3, an articulated plate 4 resting on and jointed to the chain-wheels 5, chains 7 passing around the chain-wheels 5 and the pinion 16, angle-irons 10 jointed to the chains on the chain-wheels 5 and adapted to be moved 90 by the hook 1 on the carriages or trucks colliding together and thus to turn the chain-wheels 5 and lower the plate 4 into the hooks 1, substantially as and for the purpose set forth. 95

3. A coupling for railway carriages and trucks comprising in combination a cross-beam 2 mounted on and guided between the buffers, a cross-beam 3 sliding in the cross-beam 2, U-shaped hooks 1 secured to the cross-beam 3, an articulated plate 4, resting on and jointed to the chain-wheels 5, chain-wheels 5 supported on the hooks 1, chains 7 passing around the chain-wheels 5 and the pinion 16, angle-irons 10 jointed to the chains on the 105 chain-wheels 5 and adapted to be moved by the hook 1 on the carriages or trucks colliding together and thus to turn the chain-wheels 5 and lower the plate 4 into the hooks 1, chain-wheels 20 mounted on a shaft 19 carried by 110 the beam 2, a spring likewise mounted on the shaft 19 and adapted by means of the chain-wheels 20 and chains 21 to be wound up on the articulated plate 4 being lowered, a ratchet and pawl likewise mounted on the shaft 19, 115 substantially as and for the purpose set forth.

4. A coupling for railway carriages and trucks comprising in combination a cross-beam 2 mounted on and guided between the buffers, a cross-beam 3 sliding in the cross-beam 2, U-shaped hooks 1 secured to the cross-beam 3, an articulated plate 4 resting on and jointed to the chain-wheels 5, chain-wheels 5 supported on the hooks 1, chains 7 passing around the chain-wheels 5 and a pinion 16, 120 angle-irons 10 jointed to the chains on the chain-wheels 5 and adapted to be moved by the hook 1 on the carriages or trucks colliding together and thus to turn the chain-wheels 5 and lower the plate 4 between the hooks 1, 125 and means for raising the articulated plate and thus uncouple the carriages or trucks, substantially as set forth. 130

5. A coupling for railway carriages and

trucks comprising in combination a cross-beam 2 mounted on and guided between the buffers, a cross-beam 3 sliding in the cross-beam 2, U-shaped hooks 1 secured to the cross-beam 3, chain-wheels 5 supported on the hooks 1, an articulated plate 4 resting on and jointed to the chain-wheels 5, chains 7 crossing around the chain-wheels 5 and the pinion 16, three angle-irons 10 jointed to chains 7 on the chain-wheels 5 and adapted to be moved by the ends 9 of the hooks 1 on the carriages or trucks colliding together and thus to turn the chain-wheels 5 and lower the plate 4 between the hook 1 a plate 13 underneath the beam 2 and a spring keeping said plate in its normal position, all substantially as and for the purpose set forth.

6. A coupling for railway carriages and trucks comprising in combination a cross-beam 2 mounted on and guided between the buffers, a cross-beam 3 sliding in the cross-beam 2, and adapted to be moved longitudinally relative to the beam 2, U-shaped hooks 1 secured to said beam 3, chain-wheels 5 supported on the hooks 1, an articulated plate 4 resting on and jointed to the chain-wheels 5 chains 7 passing around each chain-wheel 5 and pinion 16, angle-irons 10 jointed to the chains 7 and adapted to be moved by the hooks 1 on the carriages or trucks colliding together and thus to turn the chain-wheels 5 and lower the plate 4 between the hooks 1, means for raising the articulated plates and thus uncouple the carriages or trucks, and means for securing the hooks and corresponding parts in either the left or right hand position, substantially as set forth.

7. A coupling for railway carriages and trucks comprising in combination a cross-beam 2 mounted on and guided between the buffers, a cross-beam 3 sliding in the cross-beam 2, U-shaped hooks 1 secured to the cross-beam 3, vertically-mounted rollers 14 on the hooks 1, chain-wheels 5 supported on the hooks 1, an articulated plate 4 resting on and jointed to the chain-wheels 5, chains 7 passing around each chain-wheel 5 and pinion 16, angle-irons 10 jointed to the chains 7 and adapted to be moved by the hooks 1 on the carriages or trucks colliding together and thus to turn the chain-wheels 5 and lower the plate 4 between the hooks 1, means for raising the articulated plate and thus uncouple the carriages or trucks and means for securing the

hook and corresponding parts in either the 55 left or right hand position, substantially as set forth.

8. A coupling for railway carriages and trucks comprising in combination a cross-beam 2 mounted on and guided between the 60 buffers, rails 28 secured to the buffers 29 and adapted to guide the cross-beam 2, a cross-beam 3 sliding in the cross-beam 2, U-shaped hooks 1 secured to said beam 3, chain-wheels 5 supported on the hooks 1, an articulated 65 plate 4 resting on and jointed to the chain-wheels 5, chains 7 passing around each chain-wheel 5 and pinion 16, angle-irons jointed to the chains 7 and adapted to be moved by the hooks on the carriages or trucks colliding 70 together and thus to turn the chain-wheels 5 and lower the plate 4 between the hooks 1, substantially as set forth.

9. A coupling for railway carriages and trucks, comprising in combination a cross- 75 beam 2 mounted on and guided between the buffers, U-shaped hooks 1 suitably mounted on the end of the carriage or truck, disks or wheels 5 supported by the hooks 1, an articulated plate 4, chains 21 secured to the articulated plates 4, pulleys or chain-wheels 20 over which the chains 21 pass and means adapted to rotate the chain-wheels 20, substantially as and for the purpose set forth.

10. A coupling for railway carriages and 85 trucks comprising in combination a cross-beam 2 mounted on and guided between the hollow cross-beam 2, a facing for the cross-beam 3 against which the ends 9 of the hooks 1 bear 90 when the carriages or trucks are brought together, U-shaped hooks 1, suitably mounted on the end of the carriages or trucks, disks or wheels 5 supported by the hooks 1, an articulated plate 4, chains 21 secured to the 95 articulated plates 4, chain-wheels 20 over which the chains 21 pass, means adapted to rotate the chain-wheels 20 and means for raising the articulated plate and thus to uncouple the carriages or trucks, substantially 100 as set forth.

In testimony whereof I have hereunto set my hand in the presence of two witnesses.

AUGUST WUTHE.
